(57) **CLAIM**

What is claimed is the ornamental design for a metal bracket for supporting plywood in windows, as shown and described.

DESCRIPTION

FIG. 1 is a perspective view of a metal bracket for supporting plywood in windows, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof, the bottom plan view being a mirror image thereof;

FIG. 7 is a front elevational view of an alternate embodiment thereof;

FIG. 8 is a rear elevational view thereof; and,

FIG. 9 is a top plan view thereof, the bottom plan view being a mirror image thereof.

The broken lines showing a plywood sheet and a window frame in FIGS. 1 and 7 are included for the purpose of illustrating the invention in use, and form no part of the claimed design.
